UNITED STATES PATENT OFFICE.

PERLEY R. GLASS, OF WAYLAND, MASSACHUSETTS, ASSIGNOR TO UNITED SHOE MANUFACTURING CORPORATION, OF PATERSON, NEW JERSEY, A CORPORATION OF NEW JERSEY.

REENFORCED SHOE UPPER.

Application filed June 29, 1922. Serial No. 571,604.

To all whom it may concern:

Be it known that I, PERLEY R. GLASS, a citizen of the United States, residing at Wayland, in the county of Middlesex and State of Massachusetts, have invented certain Improvements in Reenforced Shoe Uppers, of which the following description, in connection with the accompanying drawings, is a specification, like reference characters on the drawings indicating like parts in the several figures.

This invention relates to shoe uppers provided with reenforced lacing holes. The most common type of device for reinforcing lacing holes is a metallic eyelet, and while an eyelet usually satisfies the requirements for reinforcement there are some situations where eyelets are objectionable for one reason or another. For example, a large portion of the better grades of shoes, at the present time, are provided with invisible eyelets, so-called because they do not appear on the outside of the shoe. In other words, the eyelet extends through and reinforces the interior layer or layers of the upper but does not extend through the external layer, the lacing hole in the external layer being left bare so that the shoe will not have the appearance of being eyeleted. Some reinforcement is always necessary to sustain the stresses and chafing action of the lacing, for otherwise the lacing would either tear the holes or otherwise enlarge them and distort the upper so badly as to spoil its appearance if not actually to render it unfit for service after comparatively short use.

One difficulty met in invisible eyeleting as it is now practiced is that the hole in the uneyeleted layer must be large enough to permit a clenching instrumentality to pass through it so as to clench the eyelet between two of the layers, whereas the trade demands a small hole in the uneyeleted layer, preferably so small that it will be filled by a lacing even when the latter is under tension pulling it against one side of the hole. Consequently, this demand of the trade increases the difficulty of doing invisible eyeleting satisfactorily. Furthermore, regardless of whether the hole in the uneyeleted layer is small enough to satisfy the demands of the trade it becomes stretched when the lacing is pulled tight, and wears larger at the point where the lacing chafes it, thereby exposing a portion of the eyelet.

In view of the foregoing and other difficulties an object of the invention is to provide a shoe upper having uneyeleted lacing holes so reenforced as to sustain the chafing and stresses of the lacing without injury. 60 A feature of the invention consists in providing the uneyeleted lacing holes with improved reinforcing means at the points where the lacing would otherwise injure the upper, specifically, at the points where the bights of the lacing tend to chafe and stretch the upper.

A shoe quarter usually comprises three or four layers, and my improved reinforcing device is preferably arranged to extend through all the layers to line the lacing hole and to form a bearing for that part of the lacing that extends through the lacing hole. Also, the extremities of the device are bent over upon the surfaces of the quarter, partly 70 to anchor the device, partly to clamp the layers in place, and partly to protect the surfaces against the chafing action of the lacing. The extremities may be, and the one lying on the outside surface preferably is, 80 so proportioned as to be covered and concealed by the lacing, thus leaving the lacing hole bare excepting at the portion against which the lacing is pulled. The external layer, as well as the other layer or layers, is 85 thus reenforced at the point where it is subjected to the pull of the lacing, and since the reinforce is anchored to the external layer in addition to the layer forming the opposite surface of the upper it preserves the 90 shape of the external layer and prevents the layers from being pulled or stretched unevenly.

In addition to preserving the upper in better condition and overcoming certain difficulties encountered in invisible eyeleting a reinforcing device such as that herein shown is more economical than an eyelet.

Referring to the drawings, 100 Fig. 1 is a perspective view of a shoe upper having lacing holes reenforced in accordance with this invention, the lacing holes being bare excepting at the points where the lacing will be pulled against it;

Fig. 2 is a fragmentary view showing a 105 preferred arrangement of the reinforcing elements for an oblique arrangement of the external stretches of the lacing;

Fig. 3 is a view of the reverse side of the elements shown in Fig. 2; 110

Fig. 4 is a sectional view intersecting the lacing hole reenforced according to the invention; and

Fig. 5 is a view similar to Fig. 2 excepting that the outside stretches of lacing extend squarely across from one quarter to the other and the reinforcing clips are arranged to register with said stretches.

A shoe upper of usual construction, as shown by Fig. 1, comprises an external layer 10 of leather, a lining 11 of woven material, and an inside facing 12, usually of leather. The narrow strip of relatively strong woven material, called an "eyelet stay" and heretofore interposed between the lining and the external leather 10 to insure satisfactory anchorage of invisible eyelets may be omitted without sacrificing any necessary factor when the upper is provided with reinforcing devices according to this invention. It is customary in this country to provide the quarters of the upper with eyelets before they are stitched to the vamps, and it would be consistent with such practice to provide them with reinforcing devices in accordance with this invention before stitching them to the vamps. The lacing holes 13 may be punched by any well-known or preferred machine. When the lacing holes are circular, they are preferably so small as to be filled by the lacing even when the latter is drawn to take up slack. The reinforce may be made from a strip of any suitable ductile sheet material such as brass, and is bent (see Fig. 4) to a U-shape, its bend or bends crossing its major dimension to provide confronting clamping portions and a connecting portion that extends through the lacing hole. The device shown has a clamping portion 14, two companion clamping portions 15, 15 and a connecting portion 16, and is applied to the upper so that the single tongue 14 lies on the external surface while the two tongues 15 lie on the inside facing 12 and the connecting portion 16 extends through the lacing hole and provides a lining therefor. The device is secured to the upper by pressing the clamping portions toward each other and the tips of the tongues are preferably bent inwardly to indent the upper as shown by Fig. 4 so as to increase the holding effect. The lining portion 16 is preferably curved to conform to the curvature of the hole, thereby stiffening the device, improving the bearing for the lacing, and separating the tips of the portions 15, 15. The width or minor dimensions of the strip of metal is preferably less than the diameter of the lacing and the tongue or clamping portion 14 is preferably tapered so that it will be less likely to be exposed when the shoe is laced.

According to the arrangement shown by Figs. 1, 2 and 3 the reinforce is applied to the shoe so that the tongue 14 will be oblique

with relation to the front edge of the upper, and so that when the lacing 17 is applied as shown by Figs. 2 and 3 the tongue will extend in a direction substantially parallel to the external stretch of the lacing and will be wholly concealed hereby. The diverging relation of the tongues 15, 15 broadens the bearing of the device on the inside facing so that the device is held more securely.

If it were preferred to apply the lacing so that the external stretches 18 would extend straight across the opening, that is, at right angles to the front edges of the upper, it would be preferable to arrange the reinforcing devices as shown by Fig. 5, in which case the external tongues or clamping portions 14 would be parallel to the external stretches and would therefore be wholly covered or concealed by them.

Having thus described my invention, what I claim as new and desire to secure by Letters Patent of the United States is:

1. A shoe upper provided with lacing holes which are lined in those portions only which are adjacent to the lacing slit.

2. A shoe upper provided with uneyeleted lacing holes and with reinforcing means located in said holes to protect the upper from injury under the stress of the lacing.

3. A shoe upper having uneyeleted lacing holes which are lined with metallic reinforcements in their portions adjacent to the lacing slit to receive the stress of the lacing in the wear of the shoe.

4. A shoe upper having uneyeleted lacing holes provided with metallic reinforcing members formed and arranged to be concealed by the bights of the lacing.

5. A shoe upper having uneyeleted lacing holes provided with U-shaped reinforcing members formed and arranged to hold the layers together and to prevent wear of the lacing on the outer surface of the upper.

6. An article of manufacture comprising an element of sheet material having a hole to receive a lacing, and a reinforce consisting of a strip of ductile sheet metal having one or more bends crossing its major dimension and forming two confronting portions and an integral portion connecting them, said connecting portion being arranged to extend through the lacing hole in position to sustain the tension of the lacing, and said confronting portions being arranged to clamp the element of sheet material to fix the position of said connecting portion.

7. A shoe upper having lacing holes that are bare excepting at the portions against which the lacing is pulled, and metallic clips fastened to said upper and extending through the lacing holes to furnish bearings for the lacing.

8. A shoe upper having lacing holes that are bare excepting at the portions against which the lacing is pulled, and metallic clips

each having clamping portions and an integral connecting portion arranged to underlie the lacing, said connecting portion extending through the lacing hole and said clamping portions being arranged to exercise their clamping action on opposite surfaces of the upper.

9. A shoe upper having lacing holes that are bare excepting at the portions against which the lacing is pulled, and reinforcing means fastened to the upper in position to cover said portions and sustain the stresses and chafing action of the lacing.

10. A shoe upper having lacing holes that are bare excepting at the portions against which the lacing is pulled, and sheet metal clips extending through said lacing holes and embracing said portions to furnish bearings for the lacing, each clip having portions indenting opposite surfaces of the upper to anchor the clip to the upper.

11. A shoe upper having lacing holes that

are bare excepting at the portions against which the lacing is pulled, and sheet metal clips arranged to cover said portions, each of said clips comprising confronting portions lying on opposite surfaces of the upper and a portion connecting them and extending through the lacing hole, said connecting portion being concave in cross-section to form a trough or groove for the lacing.

12. A shoe upper having lacing holes that are bare excepting at the portions against which the lacing is pulled, and metallic clips arranged to furnish bearings for the lacing, each of said clips comprising confronting portions arranged to clamp opposite surfaces of the upper and a relatively stiff portion connecting them and extending through the lacing hole.

In testimony whereof I have signed my name to this specification.

PERLEY R. GLASS.
